UNITED STATES PATENT OFFICE.

CHARLES W. HOLM, OF TROY, OHIO.

FENCE-POST.

SPECIFICATION forming part of Letters Patent No. 366,957, dated July 19, 1887.

Application filed January 29, 1887. Serial No. 225,905. (No model.)

To all whom it may concern:

Be it known that I, CHARLES W. HOLM, a citizen of the United States, and a resident of Troy, in the county of Miami and State of Ohio, 5 have invented certain new and useful Improvements in Fence-Posts; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation 15 of a fence-post, partly in section, showing same in L form. Fig. 2 is a side elevation of the same, partly in section. Fig. 3 is a view of a fence-post, partly in section, showing the same in T form. Fig. 4 is a horizontal section on 20 line x x, Fig. 1. Fig. 5 is a similar section on line y y, Fig. 3; and Fig. 6 is a detail view showing the slot N.

My invention relates to iron fence-posts; and it consists in the construction and novel combination of parts, as hereinafter described and 25 claimed.

Referring by letter to the accompanying drawings, A designates the pointed base portion 30 of a fence-post, said base portion being provided with a tapered angularly-bent anchor-plate, B, which is bolted to one face of said base portion; and has its wings C D projecting in opposite directions and at right angles to the face of the base portion A.

Above the anchor-plate B the base portion 35 A of the fence-post is provided with two bolt-holes, E F, for the reception of the bolts by which the upper portion, G, or fence-post proper, is secured.

The upper portion, G, of the fence-post is 40 made of angle-iron, either of T form in cross-section or L form in cross-section, as may be preferred. Both the T form and L form may be used at the same time in the construction of a fence.

The base portions of the fence-posts are 45 driven into the ground to the proper depth. The upper portions, G, of the fence-posts are provided through either the stem of the T- 50 post or through one of the flanges of the L-

post, as the case may be, with bolt-holes H H', which are brought into alignment with the bolt-holes E F in the upper end of the base portion A, and bolts I J are passed through the aligned bolt-holes and secured in place by 55 nuts. By this construction, when the base portions A of the posts become rusted out, the upper portions of the fence-posts may be removed and used as levers to pry the base portion out of the ground, a slot, K, in the base portion 60 communicating with the upper bolt-hole, E, in the base portion, permitting the end of the upper portion to be inserted therein for said purpose. To accomplish this, a block or stone is laid on one side of the section A, the 65 section G laid across said block or stone, and the edge of one of the flanges of which said section G is composed near the end of the section is inserted in the slot or notch K. Then by bearing down on the outer end of the lever 70 thus formed the lower section is forced up. A new lower portion may then be fitted to the upper portion, as described. The stringers L M in this construction are of wire, and the pickets may be secured to the stringers in any 75 of the ways commonly practiced.

The lower end of the fence-post proper is provided with a slot, N, which, when the upper bolt, I, is omitted temporarily or is withdrawn, permits the upper portion of the fence-post to be turned down, so that its upper end 80 may rest on the ground while the base portion is being driven into the ground. The upper portion can then be raised or turned up to place and the upper bolt, I, inserted and secured to place.

The wire stringers are secured to the end posts by hook-rods P, provided with adjusting-nuts, so that said stringers can be tightened or loosened as the temperature may demand. Staples Q are used to secure the wire stringers to the intermediate posts. These staples support the stringers loosely, so that the latter may be tightened or loosened when necessary.

Having described this invention, what I claim, and desire to secure by Letters Patent, is—

The combination of the lower or base section, tapered at its lower end and having the bolt-

holes H H' near the upper end, the anchor-plate secured to said base-section, the upper section made of angle-iron and provided in one of its longitudinal plates with the bolt-hole H', 5 registering with the bolt-hole F in the lower section, with the inclined slot or notch K, having its inner end enlarged to form the bolt-hole H, registering with the bolt-hole E, and with the longitudinal notch or slot N in the lower

end of the other longitudinal plate, and the ro bolts I and J, substantially as specified.

In testimony whereof I affix my signature in presence of two witnesses.

CHARLES W. HOLM.
